BUILDING BLOCK

Ira Foreman, San Bernardino, Calif.

Application January 30, 1940, Serial No. 316,391

1 Claim. (Cl. 72—44)

This invention relates to a building block and to a wall construction formed thereby.

An object of the invention is to provide a building block that is adapted to be employed in the erection of a hollow wall structure, and which is so formed as to facilitate the application of metallic reinforcements to the structure.

Another object is to provide a construction in a building block which will permit assemblage of vertical reinforcing rods within the body or mass of the block after the latter is set in place in a wall, and whereby vertical reinforcing rods may be passed downwardly through a series of courses of the blocks after the erection of a wall to a desired height, and whereby the rods may be imbedded in concrete after being assembled in a wall.

Another object is to provide a building block which is adapted to be set in a wall without mortar when desired and which is so formed as to permit grouting of the joints between contiguous blocks after their assemblage in a wall.

Another object is to provide a concrete building block by means of which a hollow wall may be formed comprising inner and outer wall sections that are united at frequent intervals by metallic ties so as to obviate the employment of concrete webs that are objectionable because of their tendency to conduct moisture from one wall section to the other.

Another object is to provide a building block which embodies a pair of spaced molded concrete panels connected together and held in spaced relation to each other by metallic ties in which the ties are so formed as to be readily incorporated in the block and securely anchored therein.

Another object is to provide a construction in the block panels and the metallic ties whereby the latter will serve as ties for vertical reinforcing rods applied to the blocks after or during erection of a wall of the blocks.

Another object is to provide a hollow block wall construction in which the blocks are so tied together and reinforced both vertically and horizontally as to enable the construction within limits of an earthquake-proof building.

Another object is to provide a hollow wall construction embodying superimposed rows of hollow blocks with spaced parallel reinforcing rods interposed between adjacent courses of the blocks and with pairs of parallel vertical reinforcing rods extended through openings in the blocks and arranged to overlie the outer sides of the horizontal rods in close relation thereto, and in which

ties are molded in the blocks and arranged to overlie the outer sides of the vertical rods.

A further object is to provide a concrete block and hollow wall construction so formed as to produce load supporting walls having considerable stability yet embodying a minimum volume of concrete in relation to the wall thickness, and in which an air space will be afforded between outer and inner wall sections throughout the wall structure that will serve as moisture insulation, and in which the outer and inner wall sections are tied together by a series of gussets so arranged as to permit the ready locating of service pipes or conduits within the wall structure.

With the foregoing objects in view, together with such other objects and advantages as may subsequently appear, the invention is carried into effect as illustrated in the accompanying drawings, in which:

Fig. 1 is a perspective view of the building block as seen from the outer side thereof;

Fig. 2 is a perspective view of the block as seen from the inner side thereof;

Fig. 3 is a plan view of the block;

Fig. 4 is a view in elevation, partly in section, of a fragmentary portion of a wall formed of the blocks shown in Figs. 1, 2, and 3, depicting the manner of applying reinforcing rods thereto;

Fig. 5 is a view in vertical section and elevation taken on the line 5—5 of Fig. 4;

Fig. 6 is a view in horizontal section as seen on the line 6—6 of Fig. 4, depicting the manner of imbedding the reinforcing rods in concrete after assembling the blocks in the wall;

Fig. 7 is a view in vertical section taken on the line 7—7 of Fig. 6;

Fig. 8 is a schematic view in perspective depicting the manner in which the reinforcing rods and tie gussets are relatively arranged in the wall structure;

Fig. 9 is a perspective view illustrating the manner of forming corner blocks and assembling them in a wall;

Fig. 10 is a perspective view of a T-block that is used at the juncture of an outside wall with a partition.

Referring to the drawings more specifically, 15 indicates generally the building block which comprises a pair of spaced panels 16 and 17 of corresponding marginal dimension and contour; the panels being rectangular and being formed of a suitable molded plastic material. Either one or both of the panels may be formed of cement or concrete, or they may be formed of gypsum, or 50 molded diatomaceous earth, volcanic ash, and the

like, having a cementitious binder incorporated therewith.

The panels are arranged in parallel relation to each other and are connected together by a plurality of ties 18 which are preferably in the form of gussets and comprise sheet metal plates arranged with their ends embedded in the panels 16-17. As here shown, a pair of the ties or gussets is provided for connecting the panels 16-17 and arranged in spaced parallel relation with each other and with the ends of the panels, so as to extend vertically when the block is assembled in a wall. The upper and lower edges of the ties or gussets 18 are spaced inwardly from the upper and lower edges of the panels so as to afford clearance spaces 19 between the gussets of superimposed courses of the blocks as shown in Fig. 5, through which horizontal and inclined leads of service pipes may be extended.

In order to effect secure anchorage of the ties or gussets 18 in the panels 16-17, the end portions of the plates forming same are bent at right angles to form flanges 20 which, when embedded in the panels will extend in the direction of the lengths of the panels contiguous the outer faces thereof. Apertures 21 may be formed in the end portions of the gussets 18 through which the plastic material of the blocks pass to effect an increase bond between the panels and the ends of the ties.

Extending vertically through the panels 16-17 are openings 22 which openings are arranged close to the gussets 18; the openings being disposed mediate the inner and outer faces of the panels and contiguous the inner faces of the flanges 20 so as to extend in the angle formed by the flanges 20 and so that the flanges will overlie the outermost portions of the walls of the openings.

The openings 22 in the panels are located mediate the longitudinal center of the panels and the ends thereof, so that when the blocks are arranged in a wall in broken joint formation, the openings 22 of the superimposed blocks will register with openings 22 of the blocks therebeneath thus producing columns of the openings 22 at intervals throughout the length of a wall that are adapted to receive vertical reinforcing rods which are put in place after the blocks have been assembled in a wall of predetermined height.

A longitudinally extending V-groove 24 is formed along one margin of each panel 16-17, a V-groove 25 is formed along one vertical edge thereof, and extending along the other longitudinal edge and vertical edge of each panel are ribs 26 and 27 which are adapted to seat in the grooves 24-25 of contiguous panels assembled in a wall; the ribs 26-27 being abbreviated so as not to completely fill the grooves 24-25 and thus provide spaces 28 in the bottoms of the latter. The horizontal spaces 28 in the bottoms between courses of the panels or blocks serve as channels in which horizontal reinforcing rods 29 may be disposed in the course of assembling the blocks in a wall, while the spaces 28 that occur at the ends of adjacent panels or blocks will serve in conjunction with the horizontal rod receiving channels as mortar or grout receiving channels.

In erecting a wall of the blocks 15, a course of the blocks is assembled on a foundation 30, as shown in Fig. 4, which foundation is formed with sockets 31 arranged to align with the openings 22 in the panels 16-17. The first course of the blocks disposed with their channeled edges

uppermost and are unribbed on their lower edges so as to seat on the foundation 30.

Reinforcing rods 29 are then arranged in the grooves 24 on the upper edges of the blocks, whereupon a second course of the blocks is laid with the ribs on the lower edges thereof seated in the grooves 24 of the first course. The blocks may thus be assembled in place either with mortar or with dry joints. In this fashion a wall 10 is erected of desired height, whereupon vertical rods 23 are put in place in the openings 22 by lowering the rods through the latter and seating their lower ends in the sockets 31. A thin, fluid cement is then flowed into the openings 22 so as to fill the latter and embed the rods 23 in cement cores 32 as shown in Figs. 6 and 7. Where the blocks are dry set, the fluid cement thus poured into the openings 22 will constitute a route which will flow from the openings 22 into the spaces 28 around the horizontal rods 29 and may also flow into the vertical channels between the ends of contiguous blocks. However, on filling the openings 22 with cement, the crossed rods 23 and 29 will be imbedded at their juncture in the cement cores 32 as shown in Fig. 7.

On placing the horizontal rods 29 in the channels 28 they will be located mediate the edges of the panels 16-17 so as to cross intersecting openings 22 diametrically thereof. On setting 30 the vertical rods in place they are positioned to extend along the outer sides of the horizontal rods and will thus extend along and in close proximity to the inner faces of the end flanges 20 of the gussets 18. By this construction the 35 finished wall will be provided with the arrangement of metal reinforcements depicted in Fig. 8, that is with pairs of vertical rods 23 extending over the outer faces of pairs of horizontal rods 29, and with ties or gussets 18 having end flanges 40 20 extending over the outer faces of the vertical rods 23, thus producing a fabrication of reinforcements in the spaced inner and outer wall sections of the finished wall afforded by the panels 16-17.

45 The wall formed by the blocks 15 is plastered over the outer faces of the panels 16-17 whereby the joints between contiguous blocks will be effectively sealed.

Corner blocks 15^a are provided, as shown in Fig. 9 where a wall is to be formed with a corner which corner blocks are formed as above described relative to the blocks 15 except that the panels 16-17 are formed with angularly extending end portions 33-34 adapted to afford a requisite bend or angle in a wall. T-blocks 15^b are provided as shown in Fig. 10, for use in joining partitions in which one of the panels of the block is formed with lateral extensions 35-36 adapted to be engaged with end blocks of a wall erected angularly away from a wall containing the T-blocks 15^b.

Manifestly building blocks embodying the invention may be formed of various shapes according to particular requirements but essentially will embody the arrangement of parallel panels 16-17 and their connecting ties 18, together with the openings 22 and marginal channels 24-25 and ribs 26-27 as above set forth.

70 I claim:

A building block comprising a pair of spaced parallel rectangular panels of corresponding dimensions, each of said panels having a longitudinal groove in one longitudinal edge thereof and a rib along the other longitudinal edge thereof,

said grooves having a depth exceeding that of the ribs to provide a space between the bottom of the grooves and the ribs of assembled blocks, each of said panels having openings leading therethrough from the groove to and through the rib at points between the vertical medial line and the ends of the panel through which openings

mortar may be flowed into the space between the bottom of the grooves and the ribs of assembled blocks, and gussets connecting said panels and having terminals embedded therein at points adjacent and to one side of the openings.

IRA FOREMAN.
